ROCKABLE OUTER-JAW PIPE WRENCH HAVING SLIDABLE INNER JAW ACTUATED BY ROTATABLE HANDLE

James A. Mitchell, Little Rock, Ark.

Application December 30, 1947, Serial No. 794,641

2 Claims. (Cl. 81—98)

1

This invention relates to improvements in pipe wrenches and more particularly to a quick-adjustable pipe wrench for holding or turning cylindrical bodies of various sizes.

It is among the objects of the invention to provide an improved pipe wrench which is quickly adjustable to grip cylindrical bodies of various sizes, is locked in adjusted condition against accidental slippage, automatically tightens upon a cylindrical body disposed between the jaws thereof when subjected to body turning pressure, is quickly and easily freed from its turning engagement with a cylindrical body by a short backward movement of the handle which forces the jaws of the wrench apart and eliminates sticking, is strong and durable in construction, and is economical to manufacture.

Other objects and advantages will become apparent from a consideration of the following description in conjunction with the accompanying drawings, wherein:

Figure 1 is a longitudinal elevation of a pipe wrench illustrative of the invention.

Figure 2 is a top plan view of the wrench illustrated in Figure 1.

Figure 3 is a transverse cross-section on an enlarged scale taken substantially on the line 3—3 of Figure 1.

Figure 4 is a side elevation on an enlarged scale of a fragmentary portion of the wrench showing the parts in a different operative position from that illustrated in Figure 1 and having portions broken away and shown in cross-sections to better illustrate the construction thereof.

Figure 5 is a view similar to Figure 4 showing the parts of the wrench in a still different operative position and with additional parts broken away and shown in cross-section.

Figure 6 is a view similar to Figures 4 and 5 but showing the parts of the wrench in a different position from that shown in Figures 4 and 5.

Figure 7 is an end elevation of a bracket constituting an operative component of the wrench.

With continued reference to the drawings, the improved pipe wrench comprises in general, a screw shaft 10 having a tubular, cylindrical, coaxial handle 11 on one end thereof, a bracket 12 journaled on the end of the screw shaft opposite the handle, an outer jaw member 13 pivotally connected to the bracket and an inner jaw member 14 slidably supported by the bracket and pivotally and slidably connected to the outer jaw member 13.

2

The screw shaft 10 is provided at the end thereof opposite the handle 11 with a cylindrical, coaxial arbor 15 of reduced diameter and a screw-threaded section 16 is secured on this arbor between the ends thereof and drivingly connected with the arbor by suitable means such as the keys and keyways 17 and 18 particularly illustrated in Figure 3.

Bracket member 12 is a generally rectangular body having a pair of spaced-apart, apertured substantially-parallel legs 19 and 20 in which the arbor 15 is journaled, the leg 20 being disposed between the screw-threaded section 16 and the adjacent end of the threaded portion of the screw shaft, as is clearly illustrated in Figure 5. This bracket further has a curved top portion 21 and a bottom portion 22, the two legs and the top and bottom portion being spaced apart to provide a substantially square aperture in the bracket which receives the screw-threaded section 16. The outer end of the arbor 15 is preferably beaded over, as indicated at 23 to secure the arbor in the bracket. The top portion 21 of the bracket is provided at the end thereof opposite the screw shaft with an apertured lug 24 extending beyond the end of the arbor 15 and receiving a transverse pin 25 the ends of which provides opposite shoulders disposed one at each side of the lug, and the bottom portion 22 of the bracket is provided with a longitudinal guideway 26 substantially parallel to the axis of screw shaft 10, and with an inclined cam notch 27 which is directed toward the handle end of the screw shaft at an angle of approximately 45 degrees to the screw shaft axis.

The outer jaw member 13 has a straight shank 28 of rectangular cross-section from one end of which the outer jaw 29 extends substantially perpendicular to the shank. The inner face of this outer jaw 29 is serrated or toothed, as indicated at 30, to securely grip a cylindrical body to which the wrench is applied. At its end opposite the jaw 29 the shank 28 is extended into a pair of spaced-apart, substantially-parallel plates 31 which straddle the bracket 12 and extend above and below the bracket. These plates have conversely curved upper and lower edges and cut-out portions which clear the screw-threaded section 16 as is clearly illustrated in Figure 1. The lower portions of the plates 31, at the location of inclined cam notch 27, are provided with registering apertures which receive a pin 32 which is movable in the cam notch and a pair of inclined abutments 33 are provided one on the inner side of each plate 31 at the location of the lug pin 25.

These abutments 33 are located at the side of pin 25 adjacent the handle end of screw shaft 10 and bear against the respective ends of the pin under certain operating conditions of the wrench, as will be later explained.

The inner jaw member 14 has an elongated rack bar 34 slidably received in the guideway 26 of the bracket and held by this guideway constantly in mesh with the threads of the screw shaft 10. It is here pointed out that the screw shaft threads have a very steep pitch, approximating an angle of 45 degrees, so that the rack bar 34 is rapidly advanced and retracted upon rotation of the screw shaft. An inner jaw 35 is provided at the end of rack bar 34 adjacent the outer jaw 29 and a pair of spaced-apart apertured ears 36 extend from this jaw past the shank 28 of the outer jaw, straddling the shank, and a pin 37 is secured at its ends in these apertured ears at the side of shank 28 opposite the inner jaw 25 to pivotally and slidably connect the inner jaw member to the shank of the outer jaw member. The surface of the end of the inner jaw member adjacent the shank is curved to provide a cam surface 38 and the inner face of the inner jaw 35 is provided with serrations or teeth 39 to firmly grip an object, such as the cylindrical body 40 shown between the wrench jaws in Figure 1.

The leg 20 of bracket 12 is provided with a pair of tapered stops 41 disposed one at each side of the bracket leg and engageable in corresponding notches 42 provided in the plates 31 respectively at this location and the end of the rack bar 34 opposite inner jaw 35 is slidably secured to the screw shaft by a metal loop 43 surrounding the screw shaft and secured at its ends to the corresponding end of the rack bar by suitable means, such as the pegs or rivets 44.

The operation of the wrench is substantially as follows:

In applying the wrench to a cylindrical object such as a pipe section 40, the outer jaw 29 is hooked over the object and the handle 11 is then rotated to turn screw shaft 10 to advance the rack bar 34 until the inner face of the inner jaw 35 is also brought into contact with the object. The outer and inner jaws 29 and 35 then bear against the opposite sides of the cylindrical object with a sufficient amount of pressure to set the wrench or cause it to firmly grip the object when force is applied to handle 11 to rotate the object. Before the application of object rotating force to the handle 11, the stops 41 are spaced from the bottom of the corresponding notches 42, as illustrated in Fig. 4. Pin 32 is also spaced from the inner end of notch 27. When the handle is moved clockwise, as viewed in Figure 1, the inner jaw pivots relative to the shank of the other jaw upon the cam surface 38, carrying with it the screw shaft 10 and bracket 12, and abutments 33 are brought into contact with the corresponding ends of pin 25. With the pin 25 in operative contact with the abutments 33, a leverage is exerted between the location of this contact and the location of the contact of the threads of the screw shaft with the teeth of the rack bar which leverage tends to pull the outer jaw inwardly toward the inner jaw to provide a gripping action of the wrench. This movement is limited by contact of tapered stops 41 with the bottoms of notches 42 so that the force will not be sufficient to crush an object such as a cylindrical pipe joint. When the turning force is released and the wrench backed up for another bite, pin 32 moves outwardly in notch 27 thereby separating the

inner and outer jaws and freeing them on the pipe.

The wrench is easy to adjust, may be operated very quickly and firmly grips a cylindrical object, such as a pipe joint when pipe-turning force is applied to the handle thereof. It is also extremely rugged in construction and is not easily damaged in use.

The invention may be embodied in other specific forms without departing from the essential characteristics thereof. The present embodiment is therefore to be considered in all respects as illustrative and not restrictive, and the scope of the invention being indicated by the appended claims rather than by the foregoing description, and all changes which come within the meaning and range of equivalency of the claims are therefore intended to be embraced therein.

What is claimed is:

1. A pipe wrench comprising a screw shaft having a coaxial tubular handle at one end and a pair of spaced-apart arbor portions adjacent the opposite end thereof; a rectangular bracket having spaced-apart legs journaled on said arbor portions, a lug extending beyond the adjacent end of said screw shaft, a guideway extending therethrough parallel to said screw shaft, a machined cam notch therein at the side of said guideway remote from said screw shaft, and a pair of tapered stops disposed one at each side of said guideway; an outer jaw member having a straight shank, a jaw extending from one end of said shank substantially perpendicular thereto, a pair of substantially-parallel, spaced-apart plates extending from the end of said shank opposite said jaw and straddling said bracket, said plates having apertures therein at the location of the cam notch in said bracket, and a pair of inclined abutments disposed one at the inner side of each of said plates at the location of said lug; oppositely disposed shoulders on said lug respectively engageable with said abutments; a pin extending through said cam notch and secured at its ends in said plate apertures; and an inner jaw member having a rack bar slidably in said bracket guideway and held in mesh with said screw shaft; a jaw on one end of said rack bar substantially perpendicular thereto, a pair of apertured ears on said jaw straddling said shank; and a pin secured at its ends in said ears and disposed at the side of said shank opposite said inner jaw, whereby said inner jaw is adjustably movable relative to said outer jaw by rotation of said screw shaft and said jaws are relatively moved to provide a gripping action by pressure of said abutments against said lug shoulders.

2. A pipe wrench comprising an exteriorly threaded screw shaft having a coaxial, cylindrical handle on one end, a bracket journaled on said screw shaft at the opposite end thereof and having a guideway in spaced relation beneath and substantially parallel to the axis of said screw shaft, an outer jaw member including a shank, an outer jaw on the distal end of said shank, and a pair of spaced-apart plates on the proximal end of said shank rockably straddling said bracket, a lug and an inclined abutment connection between each of said plates and said bracket disposed on each side of said screw axis, and an inner jaw member including a rack bar positioned below the axis of said screw shaft and slidably in said bracket guideway, said rack bar having teeth on its upper side meshing with the threads of said screw shaft, an inner jaw on the end of said rack bar adjacent said outer jaw, and a loop on said

inner jaw slidably and pivotally embracing the outer jaw and limiting rocking movement between the inner and outer jaws.
